UNITED STATES PATENT OFFICE.

INRANK A. PACKARD, OF DELPHOS, KANSAS.

DESIGN FOR A CULTIVATOR-KNIFE.

SPECIFICATION forming part of Design No. 14,990, dated May 6, 1884.

Application filed March 31, 1884. Term of patent 14 years.

To all whom it may concern:

Be it known that I, INRANK A. PACKARD, of Delphos, in the county of Ottawa and State of Kansas, have invented and produced a new and original Design for Cultivator-Knives, of which the following is a full, clear, and exact description.

This invention relates to the knives of cultivators for cutting the weeds in the soil and covering the seed or grain; and it consists in the configuration of such knives and their shanks, as shown in the accompanying illustration.

Reference is to be had to the accompanying drawings, forming part of this specification, in which the figure represents a view in perspective of a cultivator-knife blade and its shank, as seen from their front, embodying my new design.

15 The knife-blade A, which is of elongated form and flat on its face, presents a marginal contour of a straight lower cutting-edge, c, straight upper edge, b, parallel therewith, a straight end, d, at right angles with said upper and lower margins, b c, and a straight oppo-

site end, e, inclining so as to form an acute angle with the lower edge or margin, c, and an obtuse angle with the upper edge or margin, b, the whole forming a trapezoidal figure. The shank B rises from the upper edge, b, of the 30 knife-blade in an inclining direction laterally toward the right-angled end d, and presents a graceful curve of a concave form on its face f, of increasing width in an upward direction.

I claim—

35 The herein-described design for a cultivator-knife, consisting of a blade, A, of trapezoidal form, with its upper and lower margins, b c, parallel, its one end, d, at right angles therewith, and its opposite end, e, inclining to form an acute angle with the lower margin, c, and obtuse angle with the upper margin, b, and the shank B, of increasing width in an upward direction, of concave form on its face f, and inclining laterally toward the right-angled 40 end d of the blade, as shown.

INRANK A. PACKARD.
